* cited by examiner

Primary Examiner—Holly H Baynham*Assistant Examiner*—Cynthia M Chin(74) *Attorney, Agent, or Firm*—Panitch Schwarze Belisario & Nadel LLP(57) **CLAIM**

The ornamental design for a dart launcher toy vehicle, as shown and described.

DESCRIPTION

FIG. 1 is an elevated perspective view of the front and left side of a preferred embodiment of the dart launcher toy vehicle in accordance with the new design;

FIG. 2 is an elevation view of the left side of the dart launcher toy vehicle;

FIG. 3 is an elevation view of the right side of the dart launcher toy,

FIG. 4 is an elevation view of the front of the dart launcher toy vehicle;

FIG. 5 is an elevation view of the rear of the dart launcher toy vehicle;

FIG. 6 is a plan view of the top of the dart launcher toy vehicle; and,

FIG. 7 is a plan view of the bottom of the dart launcher toy vehicle.

The portions of the article shown in broken lines form no part of the claimed design.
